ELECTRICAL RECEPTACLE DEVICE WITH MAIN LAMP AND THERMOSTATIALLY-CONTROLLED AUXILIARY LAMP SOCKETS

Henry Herion, 216 Sutherland St.,

City Island, N.Y. 10464

Filed Feb. 12, 1968, Ser. No. 704,845

6 Claims. (Cl. 337—1)

ABSTRACT OF THE DISCLOSURE

An electrical receptacle device having a main lamp socket and an auxiliary lamp socket adapted to receive an auxiliary lamp operative only upon failure of a main lamp in the main lamp socket. The two sockets are arranged in inverted V disposition in a common housing providing a heating chamber between the socket screw-base ferrules. A spiral-wound bi-metallic conductor is arranged in the heating chamber, having one end affixed to the main lamp socket ferrule and the other end extending through a side opening in the auxiliary lamp socket ferrule for movement in and out of contact, selectively, with the screw-base electrode of an auxiliary lamp in the auxiliary lamp socket in response to temperature conditions in the heating chamber effected by non-operation and operation, respectively, of a main lamp in the main lamp socket.

In my United States Patent No. 3,321,595, issued May 23, 1967, I disclose an electric lamp receptacle device for warning of failure of an associated main lamp and at the same time providing illumination from an auxiliary lamp or lamps until the failure is corrected by replacement of the main lamp. Such devices have application particularly in multiple dwelling buildings, factories, hospitals, schools, institutions and other buildings wherein it is necessary for public safety and often required by law to have continuous illumination in hallways, stairways, at entrances, exits, in cellars etc. The device of the above-mentioned patent insures that illumination continues by the automatic energization of an auxiliary lamp upon burn-out or breakage of the main lamp, and that warning is given so that the custodian will make the necessary replacement.

The present invention has for its principal object the provision of an improved and simplified electric lamp receptacle device of the character described above and including a main socket for receiving the main lighting lamp, and an auxiliary socket for receiving either an auxiliary lamp or an extension cord plug having an auxiliary lamp or other warning device at its remote end, and including thermostatically controlled means for energizing the auxiliary socket upon failure of a lamp in the main socket, whereby said auxiliary lamp serves as notice that the main lamp has failed.

A more particular object is to provide a lamp receptacle device of the above nature wherein the main and auxiliary lamp socket ferrules are in inverted V formation within a housing providing a heating chamber therebetween enclosing a bi-metallic element. One end of the bi-metallic element is secured to the main lamp socket ferrule and the other end extends through an opening in the auxiliary lamp ferrule socket to move between positions in and out of contact with an auxiliary lamp screw-base contact shell, selectively, in response to temperature changes within the heating chamber effected by non-operation and operation respectively, of the main lamp.

Another object is to provide an improved thermostatically-controlled electric lamp receptacle device of the above nature which, because of its simplicity, low cost, compactness and ease of installation, is particularly well

2

suited to use in small apartment buildings and low cost public housing.

Other objects, features and advantages of the invention will be apparent from the following description when read with reference to the accompanying drawings. In the drawings, wherein like reference numerals denote corresponding parts throughout the several views:

FIG. 1 is a front elevational view of a thermostatically-controlled lamp receptacle device embodying the invention, shown fitted with main and auxiliary lamps;

FIG. 2 is a vertical cross-sectional view of the receptacle device, on an enlarged scale; and

FIG. 3 is a vertical cross-sectional view taken along the line 3—3 of FIG. 2 in the direction of the arrows.

Referring now in detail to the drawings, 10 designates a thermostatically-controlled lamp receptacle embodying the invention, illustrated equipped with a main lamp M, as the principal source of illumination, and an auxiliary lamp A, serving to provide illumination only upon failure due to burn-out or breakage of the main lamp, the device including heat-responsive means controlled by the energization of the main lamp for energizing the screw-base socket for the auxiliary lamp, as is hereinbelow explained.

The receptacle device 10 comprises a housing 11 having complementary, longitudinally-divided half-shell members 12, 13, which are preferably molded of a non-electrically conductive material such as Bakelite. Referring to FIGS. 1 and 2 it will be seen that the half-shell members 12 and 13 are each integrally formed with an upwardly-extending neck portion 14, and outwardly and downwardly extending shoulder portions 15 and 16 the outer ends of which terminate in opposed, inwardly-inclined end wall portions 17 and 18 defining, with said shoulder portions, a generally square shape from the upper apex of which the neck portion 14 extends. The half-shell members 12, 13 are held in assembled relation by an externally-threaded metal screw plug ferrule 19 screwed over the neck portion ends of said half-shell members, said neck portions being molded, as illustrated in FIG. 3, with external threads 20 for this purpose, and a recessed nut and bolt, indicated at 21 in FIG. 3, extending transversely through said half-shell members at a position opposite said ferrule and near the lower apices of said half-shell members.

The shoulder portions 15, 16 of the half-shell members, 12, 13 are formed with complimentary semi-cylindrical recesses 22, 22a within which are fitted metal screw-base ferrules 23, 24, respectively, said screw-base ferrules being secured in place by means of outwardly-flared outer end portions 25 thereof being interlockingly fitted within complementary annular undercuts of seats 26 formed near the outer ends of said semi-cylindrical recesses.

The outer ends of the neck portions 14 of the half-shell members 12 and 13 are formed with a tapered, rectangular opening 27 for the reception therein of a bent-metal strip 28 serving as an electrical conductor and center contact for and between the neck contact ferrule 19 and the screw-base ferrules 23, 24. To this end, the metal strip 28 is symmetrical about its longitudinal center and formed with a double-bent contact tip portion 29 extending slightly outwardly of the neck opening 27, downwardly-extending, side-by-side central portions 30, 31, outwardly-extending portions 32 and 33, respectively, and terminal end portions 34, 35, respectively, passing through slots 36, 37, respectively, formed in dividing walls 38, 39 integrally formed within the half-shell members 12, 13 at the inner ends of their semi-cylindrical recesses 22, 22a, respectively. As best illustrated in FIG. 2, the terminal end portions 34, 35 extend outwardly of the central zones of the screw-base ferrules 23, 24, respectively, and serve

as electrical contacts for the screw-base center terminals of the main and auxiliary lamps. The bent-metal strip 28 is preferably of hard brass, alloyed to provide substantial resiliency at the terminal contact ends thereof. As additional means for holding the bent-metal contact strip 28 in place, the half-shell members 12, 13 have molded therein, within the chamber 40 defined by the neck portions 14 thereof and the partition walls 38, 39, opposed posts 41, 42, respectively, the outer ends of which are bifurcated to provide a slot through which the lower ends of the central portions 30, 31 of said contact strip extend. The main lamp screw-base ferrule 24 is formed, at its inner end, with an integral, outwardly-extending tongue portion 43, extending through a slot 44 in the half-shell partition wall 39 and thence through a slot 45 in the neck portion 14, whereat it is bent double to the outside, as indicated at 46, to make electrical contact with the ferrule 19 when screwed in place upon assembly of the device as described above.

Means is provided for energizing an auxiliary lamp A screwed into the screw-base ferrule 23 only upon failure of an energized main lamp M in the main lamp socket comprising the main lamp screw-base ferrule 24. To this end, an arcuate bi-metallic element 47 is disposed within a substantially rectangular chamber 48 defined within the half-shell members 12, 13 at the lower corner or apex thereof between the screw-base ferrules 23, 24, said bi-metallic element being welded at one end to the outside of the main lamp ferrule 24. The bi-metallic element 47, as illustrated in FIGS. 2 and 3, extends down and around the nut and bolt 21 to terminate in a reversely-bent, tapered contact tip portion 49 extending through a rectangular opening 50 in the screw-base ferrule 23. It will be seen that normally, i.e. with the device deenergized, the contact tip portion 49 of the bi-metallic element 47 will be in contact with the metallic screw-base contact shell of an auxiliary lamp A screwed into the receptacle ferrule 23. In operation it will thus be apparent that when the thermostatically-controlled lamp receptacle 10 is first screwed into an electrical receptacle serving as a source of electrical supply, both the main lamp M and the auxiliary lamp A will be lighted or energized, the main lamp ferrule 24 being energized through its tongue portion 43 connected to the energization ferrule 19, and the auxiliary lamp A being energized by electrical connection with the main lamp ferrule 24 through the bi-metallic element 47, as described above. A short time after its having been energized, however, heat given off by the main lamp M will be conducted in sufficient quantity into the heating chamber 48 and to the bi-metallic element 47 therein to effect withdrawal of the tip portion 49 thereof out of contact with the metallic screw-base contact terminal of the auxiliary lamp, thereby open-circuiting the energizing connection to said auxiliary lamp, as illustrated by the broken-line representation of said bi-metallic element in FIG. 3. In this connection it is to be noted that the bi-metallic element 47 is so designed that when heated by heat radiated from the neck of a main lighting lamp M in the main lamp receptacle, and conducted to the fixed portion of the ferrule 24, it contracts radially to turn away from the screw-base of the auxiliary lamp, within the confines of the rectangular ferrule opening 50.

It is further to be understood that the auxiliary lamp A, being of substantially lesser wattage than that of the main lamp M, will not, when energized as an emergency lighting lamp, give off sufficient heat to actuate, i.e. disconnect, the bi-metallic element, inasmuch as the expansion is solely initiated from the attached end and then transmitted to the loose end for the required action.

In use, it is a simple matter to place my improved safety device in an ordinary lamp socket and place main and auxiliary lamps in the receptacle device sockets for oper-

ation as described above. Alternatively, an extension cord leading from the auxiliary lamp socket to a supervised remote place to give, by means of a lamp or other signal device, warning that the associated main lamp needs replacement, could be used.

While I have illustrated herein only one form in which my invention can conveniently be embodied in practice, it is to be understood that this form is given by way of example only, and not in a limiting sense. The invention, in brief, comprises all of the embodiments and modifications coming within the scope and spirit of the following claims.

What I claim as new and desire to secure by Letters Patent is:

1. In an electrical receptacle device with main lamp and thermostatically-controlled auxiliary lamp sockets, the combination comprising, a housing member, a neck portion extending outwardly of one end of said housing member, a cylindrical screw plug ferrule enveloping said neck portion, said housing enclosing main and auxiliary lamp sockets in mutual inverted "V" disposition at the other end of said housing, a heating chamber within said housing and between said main and auxiliary lamp sockets, said main and auxiliary sockets comprising main and auxiliary lamp socket ferrules, respectively, electrical conductor means interconnecting said screw plug ferrule and said main lamp socket ferrule, electrical circuit means interconnecting said main lamp socket ferrule and an auxiliary lamp in said auxiliary lamp socket, and heat-responsive switch means in said heating chamber operative to open circuit in response to heat generated in said chamber by an energized lamp in said main lamp socket.
2. An electrical receptacle device as defined in claim 1 wherein said heat-responsive switch means comprises an arcuate bi-metallic element having one end fixed to said main lamp socket ferrule and the other end movable, selectively, into and out of contact with the screw base shell contact element of the auxiliary lamp.
3. An electrical receptacle device as defined in claim 2 including an opening in said auxiliary lamp socket ferrule through which said other end of said bi-metallic element extends.
4. An electrical receptacle device as defined in claim 3 wherein said electrical conductor means comprises a tongue portion integrally formed with said main lamp socket ferrule and extending upwardly within said housing and through an opening in said neck portion to be contacted by said cylindrical screw plug ferrule.
5. An electrical receptacle device as defined in claim 3 wherein said housing is in the form of a pair of complementary half-shells, said cylindrical screw plug member serving to hold said half-shells together at the neck end thereof, and nut and bolt means between said sockets for holding said half-shells together at the opposite end thereof.
6. An electrical receptacle device as defined in claim 1 wherein said housing is in the form of a pair of complementary half-shells, each half-shell being formed with a recess, said recesses together defining said heating chamber, said heating chamber being entirely enclosed within said housing, said switch means comprising a bi-metallic element enclosed within said chamber.
